UNITED STATES PATENT OFFICE.

HENRY M. DRESEL, OF CHICAGO, ILLINOIS.

LOUD SPEAKER.

Application filed April 7, 1926. Serial No. 180,522.

- My invention relates to improvements in sound producers such as radio loud speakers and the like, and the chief characteristic feature is a vibrator comprising a tongue or blade resiliently held against a knife edge across the intermediate portions thereof and subjected at one end to vibrating forces such as a magnetic field controlled by the phone circuit.
- 10 The main objects of my invention are to provide an improved loud speaker or sound producer, which is clear in tone and is sensitive to the complete range of audible sounds; to provide a sound producer of simplified construction and in which the amplifying horn, having fixed resonances, may be eliminated; to provide a vibrator comprising a suitably mounted blade or resonating plate of large area which will freely and strongly vibrate to sounds; to fulcrum said blade between the ends in a suitable manner and apply the magnetic flux or other energizing means at one end so that the vibrations are also mechanically amplified; to provide a blade of such construction that the blade may be made very thin and of light material, in which the vibrations are polarized, and which is aperiodic; and to provide magnetic means wherein the poles are directly on the opposite sides of the vibrator member so that the effect of the field is not diminished when the member is vibrating and periodically moves away from the pole or poles at one side.
- 35 An illustrative embodiment of my invention is shown in the accompanying drawings, in which:
- Figure 1 is a perspective view of the sound producing unit.
- 40 Fig. 2 is a plan view of the same.
- Fig. 3 is taken on the line 3-3 of Fig. 2.
- Fig. 4 is an enlarged fragmentary view taken on the line 4-4 of Figure 3.
- Fig. 5 shows the vibrator.
- 45 In the drawings, a base or frame 1 has an integral upright portion 2 at one end and an upright lug 3 at the opposite end. A fulcrum block 4, having a blunted knife edge 5, is rigidly secured in the frame portion 2.
- 50 A U-shaped yoke 6 is adjustably secured at the ends to the upright portion 2, with a transverse portion oppositely disposed to the edge 5 of the fulcrum member 4 for holding the blade or vibrator 7 against the linear bearing 5 of the member 4. The linear edge
- 5 is shown as bearing directly on the surface of the blade 7, and on the opposite side of the blade a strip of rubber 8 is interposed between a channel-shaped bearing block 9, which is secured to the inner face of the transverse portion of the bracket 6, and the surface of the blade. In order to use very light thin material in the blade and to prevent transverse vibrations, the blade is corrugated longitudinally as shown. The rubber strip 8 conforms to the corrugated surface of the blade and may be cemented thereto. The opposite legs of the channel member 9 bear one above and one below the linear edge 5, so as to maintain the blade in an upright position. The bracket 6 is adjusted to press the blade 7 firmly against the linear bearing 5, but the rubber strip opposite the edge precludes tuning the blade to resonate to one single tone and renders the blade resonance aperiodic in character.
- With the vibrator 7 made of a non-magnetic material, such as celluloid or bakelite, an iron armature 10 is inserted in the ends of the corrugations and firmly secured to the blade by sealing wax or other means.
- Since the blade is pivoted in a linear bearing between the ends of the blade, the use of magnets on both sides of the armature is available and the electro-magnets 11 and 12 are respectively arranged on the opposite sides of the armature 10, thereby equalizing the effect of the magnetic forces when the blade is vibrated. When the armature moves away from the poles on one side, with a decrease in the effective force of the corresponding fields, the effect of the poles on the opposite side increases, so that the peaks of the vibrations are not distorted.
- As shown in the drawings, the double poled electro-magnet 11 is adjustably mounted in the upright frame portion 2, and the opposing electro-magnet 12 is mounted in the lug 3. The magnets are energized in the usual manner, as by the voice or telephone currents in radio apparatus.
- The length of the blade 7, from the lower end to the transverse fulcrum bearing 5, is so proportioned to the total length of the blade that the vibrations at the lower end are magnified by the leverages obtained.
- The vibrations in the audible range are accurately reproduced, including both the high notes and the low notes, and the various characteristics such as modulation, temper

and pitch, the improved results considered as being largely due to polarizing the vibrations in the blade by corrugating, by the non-restraining aperiodic mounting and by the mechanical amplification. Further improvements comprise applying the magnetic fluxes directly to the vibrator member and by arranging the magnets on both sides of the vibrator.

10 The vibrator plate is constructed and mounted to vibrate about an axis transverse to the length; also both sides of the vibrator are unobstructed and therefore both sides are effective for setting the air in motion to carry the sound. The mounting is such that the vibrator plate will return to the same neutral positions, so that permanent adjustments of the magnets may be made.

Although but one specific embodiment of 20 this invention has been herein shown and described, it will be understood that numerous details of the construction shown may be altered or omitted without departing from the spirit of this invention as defined by the following claims.

I claim:

1. In a sound producer, a frame having a linear bearing, a longitudinally corrugated plate secured between the ends to the linear bearing, said bearing being transverse with respect to corrugations of the plate, and

means for applying a vibrating force effective at one end of said plate.

2. In a sound producer, a frame having a knife edge, a vibrator plate, a channel member for holding the plate against the edge, the two edges of the channel member being disposed one above and one below the edge, and a resilient strip interposed between the edges of the channel member and the plate.

3. In a sound producer, a frame having a knife edge, a vibrator plate, a yoke adjustably secured to the frame for holding the plate against the edge, a channel member secured to the yoke for pressing the plate against the knife edge, and a block of resilient material interposed between the two edges of the channel member and the plate.

4. In a loud speaker, a frame having an edge, a vibrator plate, a yoke adjustably secured to the frame for holding the plate against the edge, said yoke having bearing portions on either side of the edge, a block of resilient material interposed between the plate and said bearing portions, and electro-magnets mounted in the frame and disposed on both sides of one end of the plate.

Signed at Chicago this 3rd day of April, 1926.

HENRY M. DRESSEL.
